FIRE DETECTION ALARM COVER

Stephen G. Hauser, Van Nuys, Calif., assignor to Direct Markets, Ltd., a partnership of Utah

Filed Feb. 12, 1969, Ser. No. 15,745

Term of patent 14 years

Int. Cl. D29—01

U.S. Cl. D72—1

FIG. 1.

FIG. 2.

FIG. 3.

FIG. 1 is a front plan view of a fire detection alarm cover embodying this invention.

FIG. 2 is a side elevational view of FIG. 1.

FIG. 3 is an enlarged fragmentary sectional view taken on line III—III of FIG. 1.

I claim:

The ornamental design for a fire detection alarm cover, as shown.
